UNITED STATES PATENT OFFICE.

ELBERT W. SHULL, OF COWLEY, WYOMING, ASSIGNOR OF ONE-HALF TO K. E. ANDERSON, OF COWLEY, WYOMING.

CARBON-PRODUCING APPARATUS.

1,375,234.

Specification of Letters Patent. Patented Apr. 19, 1921.

Application filed May 3, 1919. Serial No. 294,601.

To all whom it may concern:

Be it known that I, ELBERT W. SHULL, a citizen of the United States, residing at Cowley, county of Big Horn, and State of Wyoming, have invented certain new and useful Improvements in Carbon-Producing Apparatus; and I do declare the following to be a full, clear, and exact description of the invention, such as will enable others skilled in the art to which it appertains to make and use the same, reference being had to the accompanying drawings, and to the characters of reference marked thereon, which form a part of this specification.

The invention relates to means for obtaining carbon from natural or other gas, and the object thereof is to obtain the maximum amount of carbon obtainable by the ordinary burning process from a unit of gas, at the same time making it possible to use at least a portion of the by-product, heat, for other purposes.

Briefly, the invention comprises hollow, and preferably rectangular, sections mounted for reciprocation against scrapers, through which sections a fluid, such as air, is passed continuously for the purpose of cooling the sections and thus procuring a greater carbon deposit from the gas which is being burned against the under surfaces thereof. The scrapers for removing the carbon from the under sides of the sections are balanced on the sides of the hoppers into which the carbon falls, and scrapers are positioned adjacent these to remove carbon from the sides of the sections.

The sections are arranged in rows laterally and joined together in series longitudinally, each lateral unit being provided with wheeled carriages to facilitate reciprocation of the entire body of units. The ends of the body of units project through and to the exterior of the building in which the gas is being burned and one end is there connected with an air supply, while the other end has a connection for taking off the heated air by means of which it may be led off for other use such as heating green houses. In the drawings:

Figure 1 is a perspective of one end of the device and shows the operating connections between buildings.

Fig. 2 is a perspective of the opposite end of the device.

Fig. 3 is a fragmentary longitudinal sec-

tion through two hollow sections and shows a joint.

Fig. 4 is a perspective of the scraper arrangement.

Fig. 5 is an elevation showing the scraper arrangement; and

Fig. 6 is a plan thereof.

A framework 10, carrying channel bars 12, supports the operative parts of the device. The framework also supports tracks 13 on which travel the carriages supporting the sections hereinafter described, which are reciprocated by means of the gear 14, driven by shaft 15 in engagement with a rack 16. The ends of the rack 16 are connected with angle irons 17, which are bolted or otherwise secured to the hollow sections 18. The carriages for the hollow sections comprise channel irons 19, secured to the hollow sections and upon the ends of which are mounted wheels 20, by means of cross pieces 21, the wheels traveling on the tracks 13. The ends of the hollow sections are connected by means of flexible tubes 22 with air supply pipes 23, whereby air may be forced through the sections 18. The rack 16, together with gear 14 and shaft 15, as well as the tubes 22 and the air supply pipes 23, are positioned between two adjacent buildings, the building lines being indicated on the drawings. Thus the ends of the sections 18 in the opposite buildings, alternately project from the buildings a distance equal to the degree of reciprocation; the carriages and the major portions of the hollow sections are positioned in the buildings in which the gas is burned. At the opposite end of each building the hollow sections are connected by means of a hollow casting 25, having portions fitting into the ends of the sections 18 and having a hollow piston 26 projecting outwardly therefrom. The piston member 26 telescopes into a cylinder 27, in communication with a discharge pipe 28, provided with a pop-valve 29, adapted to relieve pressure in case it becomes excessive. The casting 25, as shown, is just outside the building and is adapted to be reciprocated so that the hollow member 26 passes entirely into the cylinder 27, as the entire hollow section body within the building is reciprocated. The heated air which passes to the pipe 28 may be taken off for any use, such as heating greenhouses.

Gas mains 30 run longitudinally of the

110

buildings and on opposite sides thereof, these mains having connected therewith the feed pipes 31, which supply the burners 32. Positioned directly below the hollow sections 18 are scrapers 35, adapted to scrape the under faces of said sections 18. The scrapers 35 are arranged in pairs connected by brackets 36, to which arms 37 are connected these arms being provided with looped portions 38, to engage in notches formed in the upper edge of one of the side walls of each hopper into which the carbon falls. The arms 37 are sufficiently long and heavy to slightly overbalance the scrapers 35, and thereby keep them in contact with the under faces of the sections.

To remove the carbon from the sides of the rectangular hollow sections 18, U-shaped scrapers 40 are provided, these having their vertical portions slightly concaved as shown, to present positive scraping edges to said sides. These scrapers 40 are supported on rods 41, which extend into the ends of the hoppers, the rods passing through the scrapers slightly above their centers. As shown in Figs. 5 and 6, the ends of adjacent scrapers 35 extend beyond the sides of adjacent sections and therefore beyond the upright portions of the scrapers 40, whereby swinging of the scrapers 40 on the rods 41 is limited, as the hollow sections 18 are reciprocated. It will be noted that both scrapers 35 and scrapers 40 are positioned within the hoppers 50, whereby all removed carbon falls into said hoppers.

The lower portions of the hoppers 50 discharge into conveyers 51, driven by bevel gears 52 from a drive shaft 53, these conveyers being adapted to discharge into any suitable receiver.

The detailed construction of the hollow sections is shown in Fig. 3. These sections are adapted to make a tight joint by means of overlapping parts 55, the sections being secured together by means of plates 56, held with bolts 57. Adjacent the joint there is provided in each section a hand-hole 58, through which a workman may pass one hand in the operation of securing the plates 56. These hand-holes 58 are covered by means of plates 59, held by bolts 60. Adjacent the hand-holes 58 there are provided bosses, 62, perforated at 63 for the passage of bolts by means of which the channel bars 19 of the carriages are secured to the hollow sections. This operation is also facilitated by the hand-holes 58. At the middle portion of each hollow section, a hand-hole 65 is provided and is covered with a plate 66, held by bolts 67. Adjacent this hand-hole, bosses 68 are provided and apertured to receive bolts for securing the corresponding carriage.

It is to be noted that no carriage is provided at the outer ends of the first and last

of the hollow sections, where they reciprocate through the building. This simplifies construction and is satisfactory, since the carriages used at the middle of these sections and at the first and last joints will properly support this part of the structure.

In operation, air is blown or drawn through the pipe 23 into the hollow sections by means of the flexible connections 22 and is taken from the opposite end of the device 75 by way of the piston 26 and discharge pipe 28. As the sections are reciprocated through gear 14 and rack 16, the carbon, being deposited by burners 32, is scraped from the sections by scrapers 35 and 40, and falls into 80 the hoppers 50, being conveyed away by conveyers 51. The cooling of the sections produces a much greater deposit of carbon from a unit of gas than is obtainable where I-beams or the like are used for deposit of 85 carbon without being cooled. By the present construction, much of the heat heretofore radiated from the building is taken out and can be used for other purposes, this being of considerable value in addition to the 90 increased carbon yield.

I claim:

1. In carbon-producing apparatus, the combination with gas burners of hollow sections mounted thereabove and arranged 95 alongside one another, and means to pass a cooling medium through each of said sections separately from the others.

2. In carbon-producing apparatus, the combination with gas burners of hollow sections mounted thereabove and relatively movable with respect thereto, said sections being arranged side by side, means to pass a cooling medium through each of said sections separately from the others, and 105 scrapers to engage and remove carbon from said sections.

3. In carbon-producing apparatus, a series of hollow sections joined together, and carriages for said sections. 110

4. In carbon-producing apparatus, a series of hollow sections joined together, and carriages for said sections, there being one carriage at each joint and one at the middle of each section. 115

5. In carbon-producing apparatus, hollow sections joined together, each section having a hand-hole adjacent the joints and a cover for each hand-hole.

6. In carbon-producing apparatus, the combination with a series of gas burners and a series of scrapers, of a series of hollow sections joined together and longitudinally reciprocable, means for introducing a cooling medium into one end of the series, 125 and means for removing said medium from the other end.

7. In carbon-producing apparatus, the combination with a series of gas burners and a series of scrapers, of a series of hollow 130

- sections joined together and longitudinally reciprocable, means for introducing a cooling medium at one end, comprising an air supply and flexible connections between said supply and said end, and means for removing said medium from the other end of said series, comprising a hollow piston connected thereto and coöperating with a cylinder having a discharge.
8. In carbon-producing apparatus, a U-shaped scraper having its upstanding portions concave, said portions being adapted to engage the sides of adjacent carbon-re-
- ceiving sections, and a rod passing through said U-shaped scraper. 15
9. In carbon-producing apparatus, the combination with carbon-depositing means and rectangular carbon-receiving sections, of scrapers yieldingly engaging the bottoms of said sections, and U-shaped scrapers 20 mounted adjacent the first named scrapers, the upstanding portions of said U-shaped scrapers engaging the sides of said sections.

In testimony whereof I affix my signature.

ELBERT W. SHULL.
